UNITED STATES PATENT OFFICE

BERNARD T. MURPHY, OF MARENGO, IOWA.

IMPROVEMENT IN ADJUSTABLE ROLLER-HINGES.

Specification forming part of Letters Patent No. 222,722, dated December 16, 1879; application filed June 14, 1879.

To all whom it may concern:

Be it known that I, BERNARD T. MURPHY, of Marengo, in the county of Iowa and State of Iowa, have invented a new and Improved Adjustable Roller-Hinge, of which the following is a specification.

Figure 1 is a sectional elevation of the hinge on line $y y$, Fig. 2, in position on a gate. Fig. 2 is a front elevation, partly in section. Fig. 3 is a sectional elevation on line $x x$, Fig. 2.

Similar letters of reference indicate corresponding parts.

The object of the invention is to furnish a durable and efficient device for hanging gates.

The invention consists, essentially, of an adjustable roller-hinge, by which the gate is attached to the gate-post, and which admits of the vertical adjustment of the gate and its swinging in one direction laterally.

In the drawings, A is a slotted plate of metal, held movably on the gate-post B by the bevel-headed screws or bolts a' , that pass through the slots b' ; and in a slot, c' , is pivoted a cam-lever, C, that is movable in a vertical plane, and, when passed down, will operate to push out the plate A, so that the edges of the slots b' shall bear against the beveled or conical heads of the screws or bolts a' , and the plate itself and its hinged part be thereby held in the desired position.

On a pintle, d' , that passes perpendicularly through the ears f' , that are secured on the face of the plate near its edge, is hinged the grooved roller D, so that it stands out at a

right angle to the face of the plate. On this roller is hung the gate E, the roller being clasped between two of its horizontal bars, g' g' , preferably so that it shall cross the sill F of the gate, as shown in Fig. 1, from the face of the post from which the hinge projects to the opposite face of the other post that carries the post-hooks G, on which it engages.

It will be seen that the front of the gate can easily be raised and disengaged from the hooks G, pushed back on the roller D, and swung open, and that the hinge can be adjusted by raising the lever, and then pushing the gate up or down, as may be desired, and that, when it is set as desired, it may be held in place by putting the lever down.

Having thus described my invention, I claim as new and desire to secure by Letters Patent—

1. The within-described gate-hinge, consisting of the slotted plate A, secured on a post by conical-headed screws or bolts a' , cam-lever C, pintle d' , ears f' , and grooved roller D, constructed and arranged substantially as herein shown and described.

2. In the construction of a gate-hinge, the combination of the slotted plate A, screws or bolts a' , and cam-lever C, substantially as and for the purpose described.

BERNARD TOWER MURPHY.
